GAME BOARD

Harry K. Malley, El Monte, Calif.

Application March 28, 1952, Serial No. 19,086

Term of patent 14 years

(Cl. D34—5)

To all whom it may concern:

Be it known that I, Harry K. Malley, a citizen of the United States, residing at El Monte, in the county of Los Angeles and State of California, have invented a new, original, and ornamental Design for a Game Board, of which the following is a specification, reference being made to the accompanying drawing, forming a part thereof.

The essential features of my design are shown in full lines.

I claim:

The ornamental design for a game board, as shown and described.

HARRY K. MALLEY.
